GRINDING WHEEL TRUING APPARATUS

Carl G. Flygare, Worcester, Mass., assignor to
Norton Company, Worcester, Mass., a corpora-
tion of Massachusetts

Application January 14, 1936, Serial No. 59,004

14 Claims. (Cl. 125—11)

This invention relates to grinding machines, and more particularly to a grinding wheel truing apparatus for truing the operative face of a grinding wheel in a roll grinding machine.

5 One of the objects of this invention is to provide an improved apparatus for producing a predetermined curved face or crown on the operative face of a grinding wheel, which is particularly adapted for grinding the crown on large rolls, such as are used in rolling mills.

10 A further object of this invention is to provide a simple, thoroughly practical truing apparatus in which an adjustable forming bar is utilized to cause an approaching or receding movement of the truing tool to true a predetermined curved face on the periphery of a grinding wheel. A further object of this invention is to provide an improved means for adjusting a grinding wheel truing apparatus to obtain various curvatures on 15 the operative face of the grinding wheel, so that the wheel may be trued to a predetermined operative face to produce a true cylindrical surface or predetermined convex or concave crown on the roll being ground. Other objects will be in part 20 obvious and in part pointed out hereinafter.

25 The invention accordingly consists in the features of construction, combinations of elements, and arrangements of parts, as will be exemplified in the structure to be hereinafter described, and the scope of the application of which will be indicated in the following claims.

In the accompanying drawings in which is shown one of the various possible embodiments of the mechanical features of this invention,

30 Fig. 1 is a fragmentary side elevation of the improved grinding wheel truing apparatus mounted on the grinding machine and having parts broken away and shown in section to more clearly show the construction;

35 Fig. 2 is a rear elevation of the wheel truing apparatus and its support, taken approximately on the line 2—2 of Fig. 1, having parts broken away to more clearly show the mounting of the truing attachment;

40 Fig. 3 is a fragmentary elevation of the forming bar, illustrating the mounting and the adjustment of the forming bar;

45 Fig. 4 is a cross sectional view of the forming bar, taken approximately on the line 4—4 of Fig. 3;

50 Fig. 5 is a fragmentary side elevation, partly in section, of a modification of the construction shown in Fig. 1; and

55 Fig. 6 is a fragmentary sectional view of a

modified forming bar for producing a concave crown on the grinding wheel.

As illustrated in the drawings, a fragment of a grinding machine has been illustrated, comprising a transversely movable grinding wheel 10 which is supported on a transversely movable slide (not shown), as is common practice in the grinding machine art. The grinding wheel 10 is protected by an adjustable wheel guard 11. A longitudinally reciprocable work table 12 is mounted on the usual ways on the base of the machine, such as that shown in the prior Norton Patent No. 762,838 dated June 14, 1904, to which reference may be had for details of disclosure. The table 12 is provided with a supporting surface 13 which is arranged to mate with a surface 14 on a footstock 15 which may be clamped to the table 12 by means of a clamping block 16. A stud 17 projects from the footstock 15 and passes through a clearance hole in the clamping member 16 and is provided with a washer 18 and a clamping nut 19 which serve to clamp the footstock 15 in position on the table 12.

In the grinding of a roll for a rolling mill, it is frequently necessary to grind a predetermined crown on the periphery of the roll. In order to obtain an efficient grinding action in forming a predetermined crown on the periphery of a roll being ground, it is desirable to provide a grinding wheel with an operating face which is crowned

30 so that the grinding wheel corners will not dig into the work as the roll being ground and grinding wheel are reciprocated longitudinally relative to each other during the grinding operation. In order to true the wheel to provide a predetermined curved grinding face, a truing apparatus is provided by which the wheel may be readily trued to the desired curvature. A truing apparatus is mounted on the machine so that the grinding wheel 10 and the roll being ground may be 40 traversed longitudinally relative to each other to a truing position to true the peripheral face of the grinding wheel, after which the grinding operation may be quickly and readily resumed. In

45 the preferred form of this invention, the truing apparatus is mounted in a fixed position on the footstock 15. A base or bracket 25 is held in fixed position on the footstock 15 by the screws 26 and 27. The bracket 25 is provided with two bosses 28 and 29 which extend toward the grinding wheel. The boss 29 is provided with a bushing 30 having a tapered aperture 31 which supports a center 32. The boss 28 contains a slide- 50 able, non-rotatable sleeve 33 which is held against rotation by a key 34 and is arranged to slide longi-

5

55

tudinally within an aperture 35 in the boss 28. The sleeve 33 is provided with a tapered aperture 36 which supports a center 37. In order that the center 37 may be adjusted toward and from the center 32, a manually adjustable hand wheel 40 is mounted on the outer end of a rotatable screw 41 which is screw threaded into a threaded aperture 42 within the sleeve 33. The end of the screw 41 and hand wheel 40 serve as 10 end thrust members for the screw 41 which is rotatably supported in the plate 42 mounted on the end of the boss 28.

15 A truing tool supporting member 45 is provided with countersunk apertures 46 and 47 which are arranged to be engaged by the centers 32 and 37 to serve as a pivotal support for the truing tool supporting member 45. The bracket 25 is preferably located so that the axis of the centers 32 and 37 is parallel to the axis of 20 the roll being ground and to the axis of the grinding wheel 10, so that the frame 45 may be swung at right angles to the surface of the grinding wheel 10 which is to be trued. The frame 45 is provided with an angularly disposed aperture 50 25 which is arranged to support a truing tool holder 51 carrying a diamond or truing tool 52 in the outer end thereof. The truing tool holder 51 is arranged to be clamped in adjusted position on the support 45 by means of a clamping screw 30 53 which may be actuated by a clamping handle 54.

The projecting boss 28 is preferably split so that the sleeve 33 may be clamped in adjusted position to hold the truing tool support 45 in adjusted position. As illustrated in Fig. 1, the boss 28 is provided with a radially extending slot 55. A clamping screw 56 passes through a clearance hole in the upper portion 57 and is screw threaded into the lower portion 58 so that when the adjusting knob 40 has been turned to adjust the supporting center 37 relative to its mating surface 46, the sleeve 33 may be rigidly clamped within the boss 28 to hold the parts in their adjusted position during the operation of the apparatus.

45 In order to limit the swinging movement of the support 45 so as to limit the movement of the truing tool or diamond 52 toward and from the periphery of the grinding wheel 10, a pin 60 passes through the truing tool support 45 and rides in an elongated slot 61 in a projection 62 of the bracket 25. The projection 62 extends through an aperture 63 in the truing tool support 45 and is arranged to slidably fit between the bosses 64 and 65 on the truing tool support 45.

55 To true the desired crown or curvature on the operative face of the grinding wheel, a means is provided for swinging the truing tool support toward and from the operative face of the grinding wheel to cause the diamond or truing tool 52

60 to approach or recede from the wheel so as to generate a predetermined form thereon. In the preferred construction, a forming bar 70 is pivotally mounted on a stud 71 on the upper end of the
65 truing tool supporting bracket 45. The operative face of the form 70 is preferably formed as a partial cylindrical surface, as indicated in Figs. 1 and 4. The forming bar 70 is held in place on a surface 72 on the upper end of the truing tool supporting bracket 45 by means of a pair of
70 clamping blocks 73 and 74 which are held in place on the bracket 45 by means of screws 75, 76 and 77, 78. The forming bar 70 may be clamped in rigid engagement with the surface 72 of the
75 truing tool support 45 by tightening the screws 75, 76 and 77, 78.

A follower roller 80 is rotatably mounted on a stud 81 carried by a bracket 82 which is adjustably mounted on the wheel guard 11. The bracket 42 is supported on a projection 83 of the wheel guard 11 and may be clamped in adjusted position thereon by bolts 84, the heads of which slide in a longitudinally extending T-slot 85. The roller 80 is preferably adjusted longitudinally so that its axis of rotation is in alignment with the center of the wheel, that is it lies in a medial plane 10 between the side faces of the grinding wheel.

The roller 80 preferably engages the surface of the form 70 at a point in alignment with the axis of adjustment of the forming bar 70. In the position of the parts as illustrated in Figs. 1 and 2, when the table 12 or wheel 10 are traversed longitudinally, the roller 80 will follow along an element of the partial cylindrical surface of the forming bar 70 and the truing tool 52 will generate a true cylindrical surface on the wheel 10. 20

In order to produce a crowned or curved operative face on the wheel 10, the forming bar may be adjusted or rotated about its pivot 71 so that the follower roller 80 instead of passing along an element of the cylindrical surface of the forming bar 70 will pass along a line at an angle thereto, thus causing the truing tool support 45 to be rocked about its supporting centers 32 and 37 to generate a predetermined curved face on the periphery of the wheel. To facilitate adjustment of the forming bar 70, the slotted hole 72 is provided.

the forming bar 70, its left-hand edge, as viewed in Fig. 3, is provided with gear teeth 90 which mesh with a pinion 91 carried by a stud 92. The bar 70 is unclamped by loosening the screws 75, 76, 77 and 78. The stud 92 may then be rotated to turn the pinion 91 to turn the gear segment 90 to angularly adjust the forming bar 70 relative to its supporting surface 72. To facilitate adjustment of the forming bar 70 to the desired extent in either direction, the left-hand edge of the forming bar 70, as viewed in Fig. 3, is provided with a graduated scale 95 which registers with a zero point 96 on the clamping block 73, so that the bar 70 may be readily adjusted to the desired extent to cause the desired swinging movement of the truing tool support 45 to move the truing tool or diamond 52 toward or from the wheel axis as the wheel and work are reciprocated longitudinally relative to each other to generate a pre-determined crowned or curved face on the periphery of the grinding wheel. 50

A spring 100 is interposed between the truing tool supporting member 45 and the bracket 25 and serves to maintain the forming bar 70 in operative contact with the follower roller 80 during the truing operation. The spring 100 is held within an aperture 101 in the member 45 and has its other end bearing against the bracket 25 so as to exert a pressure on the member 45 tending to move it in a counterclockwise direction. 60

The follower roller 80 is arranged to engage the partial cylindrical surface 70 of the forming bar along the element of said surface which is at right angles to the axis of adjustment of the forming bar 70 so that when the forming bar 70 is arranged with its elements parallel to the axis of the grinding wheel, the follower roller 80 will travel along an element of the surface 70 and generate a true cylindrical surface on the operative face of the grinding wheel. The axis of adjustment of the forming bar 70 is arranged at substantially right angles to a plane passing through the axis of the centers 32 and 37 and tangent to the partial cylindrical surface 70 of the forming bar. When the roller 80 and the 75

form 70 engage each other, as above described, a longitudinal traversing movement between the wheel 10 and table 12 will generate a true cylinder of revolution on the periphery of the grinding wheel. If the forming bar 70 is angularly adjusted about its axis of support, then the roller 80 will contact with the cylindrical surface 70 along a line at an angle to an element of said surface so that when the roller 80 and forming bar 70 are traversed longitudinally relative to each other, a rocking movement is transmitted to the truing tool support 45 and the truing tool 52 will generate a predetermined convex curve on the operative peripheral face of the wheel.

15 The spring 100 normally moves the truing tool carrier 45 in a counterclockwise direction (Fig. 1) and maintains the pin 60 in engagement with the forward end of the elongated slot 61 during the grinding operation. In order to facilitate 20 moving the truing apparatus into an operative position, a knob 150 is mounted on the outer end of a rod 151 which is pivotally connected to a stud 152 on the truing tool supporting bracket 45. The rod 151 is loosely journaled in a bracket 25 153 which is fixed on the upper surface of the footstock 15. In order that the parts of the mechanism may be properly adjusted so that the follower roller 80 engages the forming bar 70 at its axis of adjustment when the diamond 30 or truing tool 52 is in the center of the grinding wheel 10, it is desirable to provide an index device. In order to facilitate setting up the truing apparatus to insure the roller 80 contacting with the form 70 at the axis of adjustment of the 35 form when the truing tool 52 is in a central position on the wheel face, an index finger 154 is mounted on the bracket 153 and is arranged in the path of a zero mark 155 on the rod 15. When the zero point 155 coincides with the index finger 154, the forming bar 70 is in proper 40 relation with its pivot point so that the roller 80 will engage the forming bar 70 at its axis of adjustment when the diamond is in a central position on the operative face of the wheel.

45 During the grinding operation, as the grinding wheel is reduced in size due to wear and truing, it is necessary at intervals to adjust the wheel guard toward the peripheral face of the wheel.

50 To facilitate setting up the truing apparatus, an index finger 160 is mounted on the follower roller support 82 and is arranged in the path of a graduated scale formed on the surface 161 of the truing tool support 45.

55 A modification of the apparatus above described has been illustrated in Fig. 5, in which a forming bar 125 is pivotally mounted on a stud 126 which is supported on a bracket 127 on the wheel guard 11. The forming bar 125 is provided 60 with a partial cylindrical surface 128 which is engaged by a rotatable follower roller 129 carried by a stud 130 which is supported on the truing tool carrying member 45. The roller 129 and its supporting stud 130 are preferably carried 65 by an adjustable member 131 which is slidably mounted within an aperture 132 in the upper end of the bracket 45 and is slidably keyed thereto by a key 133. To facilitate adjustment of the follower roller 129, a manually operable 70 knob 135 is mounted on the outer end of a rotatable adjusting screw 136 which is screw threaded into a nut 137 fixed to the arm 45. The inner end of the screw 136 is provided with a reduced end portion 138 which fits within a correspondingly shaped aperture in the slidable

5 member 131. The reduced portion 138 is provided with a groove 140 by which the screw is rotatably secured to the slidable member 131 by means of a pin 141 which passes through the slide 131 and engages the groove 140 in the portion 138 of the screw 136. By rotating the knob 135, the position of the follower roller 129 may be adjusted to set up the device as desired.

10 The disclosure in the drawings, Figs. 1 to 5 inclusive, and the above description in the specification relate to a truing apparatus for truing a convex crown on the operative face of a grinding wheel. This invention, however, is equally applicable for truing a concave crown on the 15 periphery of the wheel, as will be seen in the modification illustrated in Fig. 6. A forming bar 161 has been illustrated in the drawings which may be pivotally mounted on the upper portion of the truing tool support 45 in the same 20 manner as illustrated for the bar 70. The forming bar 161 is provided with a concave curved face 162 which is formed as a partial cylinder of revolution. This curved face 162 is arranged to function in the same manner as the convex forming bar 70 shown in Figs. 1 to 5. The follower roller 80 engages the concave curved surface 162, serving to transmit motion to the truing tool support 45 to cause a concave operative face to be produced on the grinding wheel. As in the 30 case of the previously described construction, if the elements of the partial cylinder of revolution are parallel to the axis of the grinding wheel and the axis of the truing tool support, then when the grinding wheel and the work support are traversed longitudinally relative to each other, the follower roller 80 will travel along an element of the concave curved surface 162 of the forming bar and produce a true cylindrical surface on the periphery of the wheel. If the forming bar 161 is adjusted angularly relative to the truing tool supporting member 45, then the follower roller 80 will travel along the 35 line across the face of the partial cylinder of revolution which is at an angle to an element of said surface so as to cause a rocking movement of the truing tool support to generate a predetermined concave surface on the periphery of the grinding wheel.

40 Similarly, the bar 70 may be replaced by a forming bar having an irregular contour which it is desired to produce on the periphery of the grinding wheel, and this forming bar will transmit a rocking motion of the truing tool support 45 as the work support and the grinding wheel 45 are traversed longitudinally relative to each other to produce the desired and predetermined form on the grinding wheel 10.

55 In setting up the apparatus for truing a curved face on the periphery of the wheel, the table 12 or the grinding wheel 10, as the case may be, is traversed beyond a normal grinding stroke to move the truing apparatus into operative relation with the grinding wheel. When the forming bar 70 approaches the roller 80, the knob 150 is 60 pulled toward the right, as viewed in Fig. 1, to swing the truing tool support 45 in a clockwise direction so that the roller 80 will pass over the edge of the forming bar 70. The wheel 10 and table 12 are moved longitudinally relative 65 to each other until the index finger 160 coincides with a zero reading on the graduated scale on the surface 161, indicating that the truing tool 52 is in a central position on the wheel face to be trued. The truing tool 51 is previously 70

withdrawn toward the right, as viewed in Fig. 1, to an inoperative position. The wheel slide carrying the grinding wheel 10 and the wheel guard 11 and also the follower roller 80 is then moved 5 toward the right, as viewed in Fig. 1, until the zero point 155 on the rod 151 coincides with the index finger 154, at which point the roller 80 engages the partial cylindrical surface 70 of the forming bar at a point coinciding with the axis 10 of adjustment of the bar 70. The truing tool clamping handle 44 is then released and the truing tool 52 moved toward the left until it touches the peripheral surface of the grinding wheel, at which point the clamping handle 54 15 is then locked to hold the truing tool 52 in adjusted position on the truing tool support 45. If it is desired to produce a true cylindrical surface on the wheel being trued, the form 70 is allowed to remain in the position of the parts illustrated 20 in Figs. 1 and 3. If it is desired to true a convex crown on the periphery of the wheel, the form 70 is adjusted angularly relative to its support by first loosening the screws 75, 76, 77 and 78 and then turning the stud 92 to rotate the forming 25 bar 70 on its supporting stud 71 to the desired angular position relative thereto. The forming bar 70 may be adjusted angularly to a greater or lesser extent, depending upon the curvature desired to be produced on the peripheral surface 30 of the wheel. When the proper adjustment of the form has been made, the form is then clamped rigidly in position by tightening the screws 75, 76, 77 and 78. The table 12 or the grinding wheel 10 may then be traversed longitudinally to cause 35 a relative traversing movement between diamond 52 and the wheel 10. During this movement, the roller 80 will travel across the partial cylindrical surface 70 along a line at an angle to an element of said surface and will cause the truing tool 40 support 45 to rock toward and from the wheel axis so as to produce a corresponding movement of the truing tool 52 toward and from the wheel face to generate a predetermined curved face thereon. 45

It will thus be seen that there has been provided by this invention apparatus in which the various objects hereinabove set forth together with many thoroughly practical advantages are successfully achieved. As many possible embodiments may be made of the above invention and as many changes might be made in the embodiment 50 above set forth, it is to be understood that all matter hereinbefore set forth or shown in the accompanying drawings is to be interpreted as 55 illustrative and not in a limiting sense.

I claim:—

1. A grinding wheel truing apparatus for a grinding machine having a rotatable grinding wheel and a truing tool which are movable longitudinally and transversely relative to each other, a movable support for said truing tool, means to adjust the position of the truing tool relative to said support, means including an adjustably mounted cylindrical forming bar, a pivotal support for said bar which is arranged at right angles to the axis of said cylindrical surface, a follower to cause a transverse movement of said support, and means to angularly adjust the position of the cylindrical form on its pivot so that the line of contact between the forming bar and the follower roller during the longitudinal traversing movement is in a path at an angle to an element of the surface of the forming bar to cause a transverse movement of said support when the grinding wheel and truing tool are moved longitudinally.

nally relative to each other to true a predetermined curved face on the grinding wheel.

2. A grinding wheel truing apparatus for a grinding machine having a rotatable grinding wheel and a truing tool which are movable longitudinally and transversely relative to each other, a movable support for said truing tool, an adjustably mounted forming bar having a partial external cylindrical surface thereon, a pivotal support for said bar which is arranged at right angles to the axis of said cylindrical surface and passing through said axis, a follower cooperating therewith to cause a transverse movement of said truing tool support, and means to angularly adjust said external cylindrical forming surface on its pivot so that an element thereof lies at an angle to the path of movement between the grinding wheel and truing tool to cause a transverse movement of said support to true a predetermined curved face on the grinding wheel.

3. A grinding wheel truing apparatus for a grinding machine having a rotatable grinding wheel and a truing tool which are movable longitudinally and transversely relative to each other, a movable support for said truing tool, an adjustably mounted forming bar having a partial internal cylindrical surface thereon, a pivotal support for said bar which is arranged at right angles to the axis of said internal cylindrical surface and passing through said axis, a follower cooperating therewith to cause a transverse movement of said truing tool support, and means to angularly adjust said internal cylindrical forming surface on its pivot so that an element thereof lies at an angle to the path of movement between the grinding wheel and truing tool to cause a transverse movement of said support to true a predetermined curved face on the grinding wheel.

4. A grinding wheel truing apparatus for a grinding machine having a transversely movable rotatable grinding wheel, an adjustable wheel guard surrounding said wheel and movable therewith, and a truing tool which are movable longitudinally and transversely relative to each other, a movable support for said truing tool, a forming bar having a partial cylindrical surface and a follower cooperating therewith, one of which is mounted on the support and the other on the wheel guard to cause a transverse movement of said support when the grinding wheel and truing tool are moved longitudinally relative to each other, means to angularly adjust the forming bar so that the axis of the cylindrical surface is at an angle to the longitudinal movement between the wheel and truing tool to true a predetermined curved face on the grinding wheel.

5. A grinding wheel truing apparatus for a grinding machine having a transversely movable rotatable grinding wheel, an adjustable wheel guard surrounding said wheel and movable therewith, and a truing tool which are movable longitudinally and transversely relative to each other, a movable support for said truing tool, a forming bar having a partial external cylindrical surface and a follower cooperating therewith, one of which is mounted on the support and the other on the wheel guard to cause a transverse movement of said support when the grinding wheel and truing tool are moved longitudinally relative to each other, means to angularly adjust the forming bar so that the axis of the cylindrical surface is at an angle to the longitudinal movement between the wheel and truing tool to true a predetermined convex curved face on the grinding wheel.

6. A grinding wheel truing apparatus for a grinding machine having a transversely movable rotatable grinding wheel, an adjustable wheel guard surrounding said wheel and movable therewith, and a truing tool which are movable longitudinally and transversely relative to each other, a movable support for said truing tool, a forming bar having a partial internal cylindrical surface and a follower cooperating therewith, one of which is mounted on the support and the other on the wheel guard to cause a transverse movement of said support when the grinding wheel and truing tool are moved longitudinally relative to each other, means to angularly adjust the forming bar so that the axis of the cylindrical surface is at an angle to the longitudinal movement between the wheel and truing tool to true a predetermined internal curved face on the grinding wheel.

7. A grinding wheel truing apparatus for truing a curved face on a rotatable grinding wheel, comprising a rotatable grinding wheel, a frame, a truing tool support, pivotal connections between the frame and truing tool support, the axis of said pivotal connection being parallel to the axis of the grinding wheel and work support so that the truing tool support may swing toward and from the periphery of the grinding wheel, a truing tool adjustably mounted on said support, a forming bar having a partial cylindrical surface thereon which is carried by said support and arranged so that the axis of the cylindrical surface is at an angle to the longitudinal movement between the wheel and truing tool, and a follower roller adjustably mounted on the wheel guard and arranged to operatively engage the cylindrical forming bar so as to transmit a rocking motion to the truing tool support when the work support and the grinding wheel are reciprocated longitudinally relative to each other to generate a predetermined curved face on the periphery of the grinding wheel.

8. A grinding wheel truing apparatus for truing a curved face on a rotatable grinding wheel, comprising a rotatable grinding wheel, a frame, a truing tool support, pivotal connections between the frame and truing tool support, the axis of said pivotal connection being parallel to the axis of the grinding wheel and work support so that the truing tool support may swing toward and from the periphery of the grinding wheel, a truing tool adjustably mounted on said support, a forming bar having a partial cylindrical surface thereon which is carried by said wheel guard and arranged so that the axis of the cylindrical surface is at an angle to the longitudinal movement between the wheel and truing tool, and a follower roller adjustably mounted on the support and arranged to operatively engage the cylindrical forming bar so as to transmit a rocking motion to the truing tool support when the work support and the grinding wheel are reciprocated longitudinally relative to each other to generate a predetermined curved face on the periphery of the grinding wheel.

9. A grinding wheel truing apparatus for truing a curved face on a rotatable grinding wheel, comprising a rotatable grinding wheel, a wheel guard therefor, a truing apparatus base, a vertically arranged truing tool support, pivotal connections between the base and truing tool support, the axis of said pivotal connection being parallel to the axis of the grinding wheel and work support so that the truing tool support may swing toward and from the periphery of the grinding wheel,

a truing tool adjustably mounted on said support, a forming bar having a partial external cylindrical surface thereon which is carried by said support and arranged so that the axis of the cylindrical surface is at an angle to the longitudinal movement between the wheel and truing tool, a follower roller adjustably mounted on said wheel guard and arranged to operatively engage said forming bar so as to transmit a rocking motion to the truing tool support when the truing tool and the grinding wheel are reciprocated longitudinally relative to each other to generate a predetermined convex curved face on the grinding wheel.

10. A grinding wheel truing apparatus for truing a curved face on a rotatable grinding wheel, comprising a rotatable grinding wheel, a wheel guard therefor, a truing apparatus base, a vertically arranged truing tool support, pivotal connections between the base and truing tool support, the axis of said pivotal connection being parallel to the axis of the grinding wheel and work support so that the truing tool support may swing toward and from the periphery of the grinding wheel, a truing tool adjustably mounted on said support, a forming bar having a partial internal cylindrical surface thereon which is carried by said support and arranged so that the axis of the cylindrical surface is at an angle to the longitudinal movement between the wheel and truing tool, a follower roller adjustably mounted on said wheel guard and arranged to operatively engage said forming bar so as to transmit a rocking motion to the truing tool support when the truing tool and the grinding wheel are reciprocated longitudinally relative to each other to generate a predetermined concave curved face on the grinding wheel.

11. A grinding wheel truing apparatus for truing a curved face on a rotatable grinding wheel, comprising a transversely movable rotatable grinding wheel, a wheel guard therefor, a frame, a truing tool support pivotally mounted on said frame, said pivotal connections being parallel to the axis of the grinding wheel so that the truing tool may swing toward and from the operative face of the wheel, a truing tool adjustably mounted on the support, a forming bar having a partial internal cylindrical surface thereon which is carried by said wheel guard and arranged so that the axis of the cylindrical surface is at an angle to the longitudinal movement between the wheel and truing tool, a follower roller adjustably mounted on the support and arranged to operatively engage said internal cylindrical surface so as to transmit a rocking motion to the truing tool support when the work support and the grinding wheel are reciprocated longitudinally relative to each other to generate a predetermined concave curved face on the grinding wheel.

12. A grinding wheel truing apparatus for truing a curved face on a rotatable grinding wheel, comprising a transversely movable rotatable grinding wheel, a wheel guard therefor, a frame, a truing tool support pivotally mounted on said frame, said pivotal connections being parallel to the axis of the grinding wheel so that the truing tool may swing toward and from the operative face of the wheel, a truing tool adjustably mounted on the support, a forming bar having a partial external cylindrical surface thereon which is carried by said wheel guard and arranged so that the axis of the cylindrical surface is at an angle to the longitudinal movement between the wheel and truing tool, a follower roller adjustably mounted on the support and arranged to operatively engage

said external cylindrical surface so as to transmit a rocking motion to the truing tool support when the work support and the grinding wheel are reciprocated longitudinally relative to each other 5 to generate a predetermined convex curved face on the grinding wheel.

13. A truing apparatus of the type covered in claim 7 in which the operative face of the forming bar is formed as a partial internal cylindrical surface, and means to angularly adjust the position of the forming bar relative to its support so that when the grinding wheel and work support are reciprocated longitudinally, the follower roller will travel across said internal cylindrical surface 10 at an angle to an element of said surface so as to rock the truing tool toward and from the grind- 15

ing wheel to generate a predetermined concave curved face on the grinding wheel.

14. A truing apparatus of the type specified in claim 7 in which the operative face of the forming bar is formed as a partial external cylindrical surface, and means to angularly adjust the position of said forming bar relative to its support so that the follower roller will travel across the external cylindrical surface at an angle to an element of said surface so as to rock the truing tool toward and from the grinding wheel axis during the longitudinal movement between the wheel and truing tool to generate a predetermined convex curved face on the grinding wheel.
